UNITED STATES PATENT OFFICE.

HAROLD W. VANCE AND ANDREW A. MATHESON, OF DENVER, COLORADO.

CIGAR HOLDER.

Application filed September 26, 1925. Serial No. 58,876.

This invention relates to improvements in cigar holders.

It is well known among smokers that better satisfaction can be obtained from cigars if they are supported in holders which prevent the end of the cigar from becoming moist and frayed. Many different kinds of cigar holders have been made and sold, none of which have met with universal approval. One of the most serious objections to the ordinary cigar holder is that it will permit the cigar to fall out. This is very annoying and after a smoker has had the disagreeable experience of losing his cigar, he promptly discards the cigar holder and smokes his cigar in the usual manner. Inventors have recognized this defect in ordinary cigar holders and have provided them with means for positively anchoring the cigar in place and it is to this type of holder that this invention relates.

It is the object of this invention to produce a cigar holder that is provided with means for clamping it onto a cigar so that it is practicably impossible for the cigar to fall out. The means employed is so constructed that it clamps the cigar uniformly on all sides and does not comprise hooks that enter the cigars.

In order better and more clearly to describe the invention so that its construction and mode of operation may be readily understood, reference will be had to the accompanying drawing in which it has been illustrated and in which:

Fig. 1 is a side elevation showing the improved holder with a cigar in place therein;

Fig. 2 is a longitudinal section through the holder showing the parts in the position that they occupy just after the cigar has been inserted and before it has been clamped in place;

Fig. 3 is similar to Fig. 2 but shows the position of the parts after the cigar has been clamped in place, and,

Fig. 4 is a transverse section taken on line 4—4, Fig. 2.

Numeral 1 represents the mouth piece of the holder. This may be of any suitable material such as amber or some composition such as a phenolic condensation product. The mouthpiece has a small central opening 2 whose outer end is enlarged as indicated at 3 to such a size that it will receive the

end of a cigar 4 with a snug fit. Secured to the outer end of the holder is a metal ferrule 5 whose outer end is externally threaded in the manner indicated at 6. Threadedly connected to the ferrule 5 is a 60 clamping member 7 provided at its outer end with a cam surface 8. From Figs. 2 and 3 it will be seen that the clamping member has an internally threaded cylindrical portion 9 which terminates in an outwardly curved arcuate portion 10 which connects with the outwardly tapering conical cam surface 8 whose outer end is curved inwardly on a short radius so as to produce a flange 11. An endless coil spring 12 lies within the annular recess in the clamping member 7 and normally tends to occupy the position shown in Fig. 2. After the cigar is put into place, the member 7 is rotated in a direction to move it towards the position shown in Fig. 3. The spring 12 is held against longitudinal movement by the end of the holder and the ferrule 5 and will therefore be forced inwardly by the cam surface 8. In this manner the diameter of the spring 80 loop will be diminished, thereby forcing it into the outer surface of the cigar (Fig. 3). By this means the cigar becomes clamped to the holder so that it cannot be accidentally removed and lost. The metal parts 5 and 7 may be given any desired finish and give to the holder a highly ornamental appearance. The construction of parts 5 and 7 is simple and they can be manufactured very cheaply by modern machine shop 85 methods.

It is evident that the clamping means described may be employed for clamping other things than cigars and its use with cigar holders is therefore merely illustrative of 95 one of the many uses to which it can be put. Where the object to be clamped does not become excessively hot, it is evident that any other kind of compressible ring may be employed in place of the spring, as, for example, a rubber ring may be employed under suitable conditions.

Having now described the invention what is claimed as new is:

A cigar holder, comprising, in combination, an elongated mouthpiece having an axial opening enlarged at one end so as to receive the end of a cigar, a clamping member threadedly connected with the end of the mouthpiece having the enlarged open- 110

ing, said member having a portion of its interior formed into an annular conical cam surface, an annular resilient ring operatively associated with said surface, said surface tapering inwardly and away from the end of the mouthpiece to which it is attached whereby when it is rotated in such a direc-

tion that it moves onto the mouthpiece the ring will be reduced in diameter.

In testimony whereof we affix our signatures.

HAROLD W. VANCE.
ANDREW A. MATHESON.
